UNITED STATES PATENT OFFICE.

WILLIAM B. MANGOLD, OF CHICAGO, ILLINOIS, ASSIGNOR TO VORTEX MFG. CO., A CORPORATION OF ILLINOIS.

CUP DISPENSER.

Application filed April 2, 1924. Serial No. 703,638.

This invention relates to a cup dispenser, and more particularly to a dispenser for flat cups of sector-shape adapted to be placed in a stack within a slotted container 5 having a pivoted cover and a pivoted cup aligner mounted on the container back plate, said container being pivoted on a back mounting plate so that the aligner leaning against the mounting plate, when 10 the container is being filled with cups, will act to tilt the cups into proper dispensing position when the filled container is swung upwardly toward the mounting plate to permit the aligner to project into the slotted 15 back plate of the container.

It is an object of this invention to provide a flat cup dispenser wherein the cup container is slotted and has an aligner pivoted on the back thereof to project into the container to tilt the cups therein when the container is raised and engaged on the mounting plate.

It is also an object of the invention to provide a flat cup dispenser wherein a pivoted cup container is provided with a cup aligner which is adapted to be swung into the container and locked thereto to first tilt and then hold the flat cups in properly inclined dispensing position.

It is a further object of this invention to provide a flat cup dispenser wherein a slotted container is equipped with a pivoted cup aligner adapted to be locked to the container in closed position to hold the flat cups within the container properly inclined against jamming.

It is an important object of this invention to provide an improved flat cup dispenser wherein a container has a cup aligner pivoted on the exterior thereof and constructed to be projected through a slot in the container to gradually tilt the cups starting from the lower end of the container and working toward the top, after which the aligner is locked to the container, thereby acting to hold the cups tilted ready for easy removal from the lower dispensing end of the container.

Other and further important objects of 50 this invention will be apparent from the disclosures in the specification and accompanying drawings.

This invention (in a preferred form) is illustrated in the drawings and hereinafter more fully described.

55

On the drawings:

Figure 1 is a side elevation of a flat cup dispenser embodying the principles of this invention.

Figure 2 is a reduced rear view thereof. 60

Figure 3 is a rear view of the dispenser with the mounting plate broken away.

Figure 4 is a fragmentary transverse section taken on line 4-4 of Figure 3.

Figure 5 is a transverse section taken on 65 line 5-5 of Figure 1.

Figure 6 is a longitudinal vertical section of the dispenser in open position with a flat cup carton partly withdrawn leaving the flat cups within the dispenser.

70

Figure 7 is a similar section with the cup container nearly closed.

Figure 8 is a vertical longitudinal section of the dispenser in closed position.

Figure 9 is an enlarged fragmentary detail sectional view taken on line 9-9 of Figure 7.

75

Figure 10 is a fragmentary side view of the lower end of a modified form of a cup container.

80

Figure 11 is a detail section taken on line 11-11 of Figure 10.

Figure 12 is a rear view of the upper end of a modified form of a dispenser with the mounting plate omitted.

85

Figure 13 is a fragmentary detail section taken on line 13-13 of Figure 12.

As shown on the drawings:

The flat cup dispenser comprises a metal mounting plate 1 having a plurality of 90 apertures 2 therein for receiving mounting screws for the purpose of securing the dispenser to a wall. Struck inwardly from the upper portion of the mounting plate 1 are a pair of stop lugs 3 leaving the apertures 4 illustrated in Figure 2. The mounting plate 1 is provided with integral forwardly directed longitudinal flanges 5, each of which is formed with a notch 6 in the upper end thereof.

95

Supported by the lower ends of the mounting plate flanges 5 is a shaft or rod 7 which projects through slots 8 provided in the lower ends of a pair of longitudinal

100

parallel side walls 9 forming part of a flat cup container. The container side walls 9 are integrally formed at right angles to a container back plate 10 having a longitudinal opening or slot 11 extending through the center thereof. Integral with the side walls 9 are inclined side walls 12 which converge and are integral with a narrow front plate 13, the lower end of which is bent outwardly to form a thumb piece 14. Each of the container inclined side walls 12 is provided with an upwardly and rearwardly inclined slot 15 which extends from the front plate to within a short distance of the side walls 9. Secured to the inner surfaces of the container side plates 12 below the inclined slots 15 are the flanges 16 of a downwardly curved or concave cup supporting shelf 17. A flanged cover 18 is pivotally supported on the upper end of the container back plate 10 and has a spring latch 19 formed on the front end thereof to snap over a projection 20 formed by slightly bending out the upper end of the container front plate 13.

Supported on the exterior surface of the lower portion of the container back plate 10 is a rod or shaft 21 on which the lower end of a pair of flanges 22 are pivoted. The flanges 22 are integrally formed on the longitudinal edges of a channel shaped cup aligner 23 which is adapted to project into the container through the back slot 11. A bracket 24 is spot welded within the upper end of the channel aligner 23 and pivoted on said bracket 24 is a latch or locking bar 25 provided with an integral handle or arm 26 on which a thumb piece 27 is integrally formed. The ends of the latch bar 25 are inclined as illustrated in Figure 9 and are adapted to engage through slots 28 in the side walls of the channel aligner 23 and project behind the slot forming edges of the container back plate to hold the aligner locked in closed position, projecting into the container slot 11 to hold a stack of flat sector shaped paper cups 41 with the cups properly inclined so that they may be readily removed one at a time through the container outlet slots 15.

Figures 10 and 11 illustrate a modified form of a dispenser container having a cup shelf 30 provided with lugs 31 which are spot welded to the inner sides of the container side walls 12. Flange portions 32 integral with the sides of the shelf are seated in recesses formed in the inclined slots 15, as shown in Figure 10.

Figures 12 and 13 illustrate the upper portion of a flat cup container equipped with a modified form of latching mechanism for the cup aligner. Pivoted mounted on the hinge pin 33 of the container cover 34 is a sleeve 35 which is integrally formed on one end of a latch spring shaped as illustrated

in Figure 13 with curved portion 36, a flat plate 37, and a thumb piece 38. When the aligner 23 is in its closed position the pivoted latch is swung inwardly into the channel aligner 23 with the curved portion 36 of the latch springing over the upper end of the back plate of the aligner and with the latch plate 37 positioned against the outer face of the channel aligner back plate. The aligner is thus held in closed position to retain the flat cups properly inclined within the container ready to feed downwardly into dispensing position without danger of jamming.

The operation is as follows:

The improved dispenser of this invention is adapted to be secured in place on a wall in Pullman cars, railway coaches, adjacent drinking fountains, or in any other desired places where drinking cups are required.

The mounting plate 1 is mounted on a wall by means of retaining screws which are engaged through the apertures 2 of said mounting plate. This is done when the container is swung into open position. When in position for use the container is engaged on the mounting plate 1 as illustrated in Figure 1. The lugs 3 serve as stops against which the flanges 22 of the cup aligner 23 are adapted to seat when the container is in position for use. To fill the container it is lifted slightly to disengage the ends of the hinge pin 33 from the notches 6 formed in the flanges 5 of the mounting plate 1. The container is then swung downwardly into the position illustrated in Figure 6, and the cover 18 is opened. The aligner latch bar 25 is moved into unlocked position by means of the handle 26 and thumb piece 27. The pivoted aligner 23 is swung outwardly about its pivoted end to lean up against the mounting plate 1, as shown in Figure 6. A carton 40 full of flat paper cups 41 has the bottom flaps torn off and the open, bottom end of said carton is inserted into the container up against the shelf 17. The container is then swung upwardly toward the position illustrated in Figure 7, and the carton 40 is pulled out of the container depositing the paper cups. The cover 18 is then closed.

The aligner 23 is pushed upwardly with the raising of the container, and as the rear of the container approaches the aligner the lower end of said aligner first enters the lower end of the container slot 11 and engages the lowermost flat cups 41 in the container and acts to tilt said cups moving the open or arc shaped ends of the cups upwardly while the tips of the flat cups move downwardly. When the container reaches a position similar to that shown in Figure 7 the aligner is swung away from the mounting plate 1 and enters the container slot 11, thereby aligning the flat cups in inclined position as shown in Figure 8 to obviate

jamming of the cups and positioning the same so that they will feed downwardly toward discharge position.

When the aligner is properly projected into the container to align the cups, the locking bar 25 is swung into locking position as illustrated in Figure 9, with two diagonally opposite ends or corners of said bar projecting through the slots 28 behind the back plate 10 of the container. The aligner is thus locked in closed position with the aligner flanges 22 contacting the outer surface of the container back plate to limit the inward movement of the aligner. With the container closed and the aligner locked to hold the cups properly stacked in inclined position the container is swung toward the mounting plate 1 and lifted to permit the ends of the hinge pin 33 to be seated in the notches 6 of the mounting plate flanges 5.

To remove a cup from the container it is only necessary for a person to place a thumb against the top of the thumb piece 14 and the index finger against the folded tip end of the lowermost cup in the container. The lowermost cup may then be readily pulled out of the container against the pressure caused by the weight of the cups remaining in the container. The inclined cups drop by gravity in the container after the removal of each cup.

I am aware that numerous details of construction may be varied through a wide range without departing from the principles of this invention, and I therefore do not propose limiting the patent granted otherwise than necessitated by the prior art.

I claim as my invention:

1. A flat cup dispenser comprising a mounting plate, a slotted container pivotally and shiftably mounted on said mounting plate, a flanged aligner pivoted on the container adapted to be projected into the slotted container to align the cups therein,

and a locking mechanism on the aligner for retaining the aligner locked to the container with the flanges of the aligner contacting the container to limit the movement of the aligner into said container.

2. A flat cup dispenser comprising a mounting plate, notched flanges formed thereon, a container having side slots and a rear slot therein, a hinge pin supported on the container, a container cover pivoted on said hinge pin, said container adapted to be lifted and then lowered to permit the ends of the hinge pin to seat in the notched flanges of the mounting plate, an aligner pivoted on the container adapted to project through the container rear slot to align cups within the container, flanges formed on the aligner adapted to limit the movement of the aligner into the container, and means for locking the aligner in its closed position.

3. In a flat cup dispenser the combination with a container having a longitudinal slot in the rear thereof, a flanged aligner pivoted on the exterior of the container adapted to be swung into closed position to project into the container through said slot to tilt cups within the container, and means on the aligner adapted to engage the container for locking the aligner in closed position.

4. A flat cup dispenser comprising a slotted container, means for supporting the same, a channel member pivoted on the container adapted to be projected into the slotted container to tilt and hold cups in inclined position against jamming, stops on said channel member for limiting the movement of the channel member into the container, and a latch mechanism on said channel member for holding the same locked to the container.

In testimony whereof I have hereunto subscribed my name.

WILLIAM B. MANGOLD.
